UNITED STATES PATENT OFFICE.

WALKER STANSELL, OF MEMPHIS, TENNESSEE.

EXCAVATOR.

1,137,171.

Specification of Letters Patent. Patented Apr. 27, 1915.

Application filed June 3, 1914. Serial No. 842,392.

To all whom it may concern:

Be it known that I, WALKER STANSELL, a citizen of the United States of America, residing at Memphis, in the county of Shelby and State of Tennessee, have invented certain new and useful Improvements in Excavators, of which the following is a specification.

The present invention relates to improvements in excavators and is especially designed for the purpose of building levees. The invention as physically embodied contemplates a bucket with a carrying apparatus and equipped with loading and dumping means whereby, in the building of a levee, the soil may be loaded at a distance and by a succession of manipulations be brought to the levee and dumped at the desired location. While I shall hereinafter refer to the apparatus as applied to building a levee, it will of course be understood that this is done merely for convenience of illustration, as the apparatus may of course be used for loading, transporting and unloading other material for other purposes.

The invention consists in certain novel combinations and arrangements of a conveyer bucket with its loading, unloading and traversing means associated with an operating tower and hoisting devices, as will be hereinafter set forth.

In the accompanying drawings I have illustrated one example of the physical embodiment of my invention constructed according to the best mode I have so far devised for the practical application of the principles of my invention.

Figure 1 is a diagrammatic view of the excavating apparatus complete, showing the conveyer bucket in loading, unloading and return positions. Fig. 2 is a plan view of the "deadman" or anchoring cable for the main or track cable of the apparatus. Fig. 3 is a rear elevation of the tower, as seen from the left Fig. 1. Fig. 4 is an elevation of a portion of the tower from the front or right of Fig. 1. Fig. 5 is a side view of the tower as shown in Fig. 1. Fig. 6 shows a modified form of using the hoisting line between the carriage and the bucket by means of which the vertical lift of the bucket is varied with relation to the pull on the hoist-dump line to cause dumping of the bucket at different locations or distances from the tower.

I do not claim herein any particular form of dumping bucket or carriage, as the bucket may be of any suitable form or type as indicated at 1, while the carriage indicated at 2 may be similar to the carriage and its releasing device as illustrated in my co-pending application for Patent Ser. No. 827,422 filed Mch. 26, 1914.

The bucket carriage 2 is adapted to travel backward and forward on the main or track cable 3 which is suspended between the sheave 4 at the top of the tower 5 and the sheave 6 on the "deadman" or anchoring cable 7. This cable 7 is arranged horizontally above the surface of the ground, between the two posts 8, 9, and the sheave 6 is adapted to travel between the posts to accommodate the excavator as its operations progress.

The track cable 3 at its tower-end is provided with a counterweight 10, weight cable 11 and sheave 12, the cable passing over the sheave which is fixed at the end of the cable 3, and thence to a winding drum 13 supported upon the base 14 of the tower. The weight 10 is adapted to move vertically to take up slack and provide a uniform tension for the track cable, and guides 15 are provided for the movement of the weight, while an idler pulley 16 is furnished for the weight cable 11, as best seen in Fig. 5. The track cable is wound upon its drum by means of an engine or motor which is typically represented at 17 on the base of the tower (see Fig. 3) and it should be understood that the counterweight is furnished to maintain a uniform tension after the cable has been wound upon the drum.

During the process of loading the bucket 1 it is to be dragged over the surface of the ground until a sufficient quantity of loose soil is scooped into the bucket, and then by means of the loading cable 18 the loaded bucket will be drawn over the surface of the ground to the dumping point. The loading cable 18 passes over a sheave 19 to the winding drum 20 on the base of the tower, by means of which drum the cable is wound when the bucket is loaded and being dragged or pulled toward the dumping point, and the sheave 19 is journaled in a casing 21 which is vertically adjustable in the tower to adapt the loading cable for different altitudes of the bucket while in use. To guide the casing 21 in its vertical adjustment I

provide the vertically arranged posts 21', four in number, which are adapted to support the casing in desired position. The rope 18 is attached to the forward or working end of the bucket as it is hauled to the dumping point by the hoisting drum. A second cable or cord 22 is connected to the bucket as shown, and as illustrated in the showing of the invention this cord is the dumping cable or line for the bucket. The dumping cable is attached at one end to the carriage as indicated at 24 and is passed through a sheave 25 on the bucket from which point it passes over the sheave 26 on the carriage, and thence by way of the sheave 27 on the tower to the winding drum 28 on the base of frame of the tower. This cord or cable is also supported on an adjustable sheave in the tower, and the sheave 27 is journaled in the adjustable casing 29 supported in the guide posts 21'. Thus by means of their adjustably supported sheaves the two cables 18 and 22 may be worked from adjusted positions depending upon requirements of the apparatus.

The three winding drums 13, 20 and 28 are driven from the engine or motor 17 to wind their cables. When unwinding and paying out from their drums 20 and 28, the two cables 18 and 22 are assisted each by a weight as 29 which is suspended over a sheave 30 by its cord 31 or 32. The cord 31 is wound upon a spool 33 that revolves with the drum 28 and the cord 32 with its weight attached is wound upon a spool 34 on the drum 20. By the utilization of these weights and cords and their winding spools, when the two cables 18 and 22 are being wound upon their drums these weights are lifted. When the empty bucket is being returned for another load and the cables 18 and 22 are running free and unwinding from their drums, the weights will descend and their potential energy assists to overcome the friction of the released drums. This reduction of friction permits the carriage, as it rolls down the cable track by gravity, to pull the cables and the carriage is permitted to run quickly to the loading point.

Referring to the counterweight 10 it will be observed that when this weight is seated or supported as upon the table 10' indicated just below the weight in Fig. 5, its cable 11 may be unwound from the drum to permit the track cable 3 to sag as required and the machine may then be used as a slack line excavator without uncatching the bucket from the carriage.

The operation of the device thus far described, briefly is, starting with the bucket supported by the carriage in dotted lines at A near the tower, the carriage runs down the track cable by gravity and unwinds the loading and dumping lines, the weights 29

relieving the drums of friction as described and enabling the carriage to pull out the cables more freely. When the position B has been reached the bucket is freed from the carriage, in required manner, (as for instance by the releasing device in my application for patent above mentioned) the dumping line being held by its drum. The bucket is now placed in position to scoop or dig up the soil (as shown at B) and the loading drum is operated to draw on loading cable 18 to load the bucket, the cable 22 being used to tilt the bucket for loading. After the bucket is loaded, the continued winding of the drum 20 pulls the bucket toward the tower or dumping place C, and at this point the dumping line 22 is wound about its drum at a speed to cause the bucket to stand up on end and spill its contents as it is being hauled up the levee or embankment by the cable 18. After the contents of the bucket is emptied, by means of the two drums 20 and 28 the bucket is hoisted to full position of the carriage in Fig. 1, the bucket is latched in suitable manner to the carriage, and then the carriage is again permitted to return for another load. As the work progresses the tower, which is supported upon three wheeled-trucks as 35, 36, 37 which are adapted to travel upon the track rails 38, may be moved along the rails and the sheave 6 will also travel along the anchor cable 7 as the tower is moved, thus moving the track cable to desired position. After an area as wide as the length of the anchor cable 7 has been worked, the cable is removed from one of the posts 8 or 9, the post removed, and located in another position, and then the cable is again attached to its post, and in this manner the anchored end of the track cable is moved with the tower end of the track. The result of the operations is illustrated in Fig. 1 where the embankment or levee is shown in process of building.

Having thus fully described my invention, what I claim as new and desire to secure by Letters Patent is:

1. The combination in an excavating apparatus with a tower and a track cable having one end anchored, of a winding drum on the tower, a sheave on the free end of the track cable, and a tension cable on the drum passed over said sheave and having a counterweight at its end whereby a uniform tension is preserved in the track cable.

2. The combination in an excavating apparatus with a gravity traveling carriage and its bucket, of a loading cable attached to the bucket and a winding drum for the cable, a dumping cable attached to the carriage and supporting the bucket and a winding drum for said cable, a winding spool for each drum, a cable passed over each spool and a weight on each cable, whereby when

the carriage is traveling by gravity the weights assist in unwinding the cables from the drums.

3. The combination in an excavating apparatus with a track a carriage thereon and a bucket, of a pair of winding drums, a dumping cable extending from one drum and attached to the carriage having operative connection with the bucket, a loading cable from 10 the other drum to the bucket, a tower, and vertically adjustable supporting sheaves in the tower for said cables.

4. The combination in an excavating apparatus including a movable wheeled tower 15 and its rack and an anchoring cable parallel with the track, a traveling device on the anchoring cable, a track cable suspended from the tower and having one end connected to the traveling device, a winding drum on the 20 tower, a sheave on the free end of the track cable, and a tension cable on the drum passed over said sheave and having a counterweight at its end whereby a uniform tension is preserved in the track cable.

5. The combination in an excavating apparatus with a suitably supported track cable and a carriage thereon, of a bucket suspended from the carriage, an operating cable attached to the carriage, and a winding drum for said cable, a winding spool, and a 30 weighted cable passed over the spool and drum for unwinding the operating cable from the drum.

6. The combination in an excavating apparatus including a movable wheeled tower 35 and its track and an anchoring cable parallel with the track supporting a traveling device, a track cable supported between the tower and traveling device, a winding drum on the tower properly supported, and means 40 between said drum and support for the track cable for taking up slack of the track cable.

In testimony whereof I affix my signature in presence of two witnesses.

WALKER STANSELL.
